UNITED STATES PATENT OFFICE.

EDGAR M. HAWKINS, OF ROCHESTER, NEW YORK, ASSIGNOR TO M. D. KNOWLTON COMPANY, OF ROCHESTER, NEW YORK, A CORPORATION OF NEW YORK.

FOLDING PAPER-BOARD BOX AND STAY THEREFOR.

1,102,750.

Specification of Letters Patent.

Patented July 7, 1914.

Application filed August 3, 1912. Serial No. 714,152.

To all whom it may concern:

Be it known that I, EDGAR M. HAWKINS, citizen of the United States, and resident of Rochester, in the county of Monroe and 5 State of New York, have invented certain new and useful Improvements in Folding Paper-Board Boxes and Stays Therefor, of which the following is a specification.

This invention relates to folding paper- 10 board boxes and fastening stays therefor, and one of the principal objects of the invention is to provide means for reducing the danger of a fastening stay on the edge of a box being stripped, torn or rubbed 15 off from the box.

In the manufacture of folding or knock- 20 down paper-board boxes it is customary to score and cut a one-piece blank along suitable lines for permitting the folding or setting-up of the blank into box form. It has also been customary to join the ends of the blank at one edge of the box by an adhesively applied fastening stay, in the form 25 of a strip of strong sheet material. Such stay has generally been applied to the adjoining side-wall sections of the blank with its ends overlapping onto the end wall sections, and in setting up the boxes with the fastening or joining stay applied in such 30 manner, it has been the practice to slit the overlapping ends of the stay back lengthwise thereof with a sharp knife to permit of the end wall sections being folded down onto each other in usual manner. Some 35 have held that this slitting of the stay facilitated the tearing of the same, while others have held that the tendency of the stay to tear when slit and folded around the corner of a box in this manner was no 40 greater than when the stay was cut shorter and applied with square ends terminating at the edges of the side wall sections. However this may be, a stay so formed at its end as to have a substantially U-shaped 45 opening—that is, a stay in which a substantially U-shaped piece with the closed end of the U facing inward is cut bodily out of the end of the stay—is much superior to either of the others just described, as there

is much less tendency for a tear to start 50 in the tape. This is especially the case with stays made of strong textile fabric or tape in which the closed end of the U-shaped cut runs substantially in the direction of the woof of the fabric in which case it is 55 exceedingly difficult to tear against the woof threads.

An important object of the present invention is to prevent this tearing of box-stays, and the result is obtained by making use 60 of stays substantially of the type just described, that is to say, by employing a stay in which the end is bifurcated in such a manner that a piece is taken bodily out of the end of the stay, which piece when re- 65 moved leaves a longitudinal opening or cut-cut portion the inner end wall of which is defined by a line running in a general direction crosswise of the stay.

Other features of the invention not hereinbefore referred to will be hereinafter described and claimed and are illustrated in the accompanying drawings, in which,

Figure 1 is a plan of a portion of a finished paper-board box blank—that is, a 75 paper-board box complete except for setting it up—having applied thereto a stay such as hereinbefore described, and Fig. 2 is a perspective of the same showing the parts in the positions they assume at one 80 corner of the box when the finished blank is set up in box form.

Similar characters designate like parts in all the figures of the drawings.

B designates in a general way a portion 85 of a finished box blank in its unfolded or spread-out state. Four adjoining sections or walls of this blank or box are illustrated, the same being designated respectively by 2, 3, 4 and 5. Here the sections 2 and 3 90 represent side walls of the box, while 4 and 5 may be end flaps for forming one end or the top of the box. These parts are or may be substantially of the usual and ordinary construction, they being formed from 95 a blank suitably scored and cut along intersecting lines, such as 6, 7, 8 and 9, for permitting the proper folding of the dif-

ferent sections at the edges represented by said lines. It has been customary to join the two ends of the finished blanks by a fastening or joining stay of suitably strong and flexible material. A stay or piece of tape similar in most respects to the stays heretofore employed is indicated at 10. It is applied in well-known manner to adjoining sections of the box or finished blank 10 so that approximately half of the main portion of the stay will adhere to one sectional wall 2 and the other half to the adjoining sectional wall 3 of the box, any suitable adhesive being employed for the purpose of causing it to adhere. At its ends, however, this stay differs from those heretofore employed in that a portion of it is cut out lengthwise of the strip to leave a substantially U-shaped opening, that is, an 15 opening having an end wall defined by a line running in a general direction crosswise of the strip. The two ends or forks formed by bifurcating one end of the stay in this manner are caused to adhere to the 20 two sections or flaps, such as 4 and 5, that are intended to be folded down onto each other to form one end—such as the top—of the box. Preferably the opening formed by bifurcating the end of the stay is substantially U-shaped or semi-elliptical, as illustrated at 11, the forked ends resulting from 25 dividing the stay in this manner being indicated at 12 and 13.

It will be seen that the inner end wall of 30 the opening 11 runs substantially in the same general direction as the woof of the tape from which the stay is formed, and that it is therefore exceedingly difficult to tear the stay lengthwise. Moreover, it will be 35 seen that when the box is set up, as illustrated in Fig. 2, the shape of the inner walls of the forked ends 12 and 13 of the stay is such as to reduce to the minimum the danger of the stay being torn or rubbed off as a result of catching on an obstruction or otherwise. Because of these things a box provided with a fastening stay constructed and applied substantially in the manner described and illustrated, has great advantages 40 over those heretofore used and is afforded a much better protection at the corners thereof.

What I claim is:—

1. A folding box of paper-board or like 45 material, comprising a blank scored and cut to form a plurality of walls two of which are adapted to be folded down onto each other to positions in which they are in planes substantially perpendicular to the planes of 50 two adjoining walls, in combination with a stay comprising a strip of sheet material having a longitudinally bifurcated end the opening in which is substantially U-shaped with the closed end of the opening facing inward.

with the closed end of the opening faced inward and located substantially at the corner 65 of said four walls and the forks of said bifurcated end adhering to the two walls which are adapted to be folded down onto each other and with the body portion of the strip adhering to the other two walls. 70

2. A folding box of paper-board or like material, comprising a blank scored and cut to form a plurality of walls two of which are adapted to be folded down onto each other to positions in which they are in 75 planes substantially perpendicular to the planes of two adjoining walls, in combination with a stay comprising a strip of textile fabric having a longitudinally bifurcated end the opening in which is substantially U-shaped with the closed end of the opening facing inward and located substantially at the corner of said four walls and running in the general direction of the woof of the strip and with the forks of said bifurcated end adhering to the two walls which are adapted to be folded down onto each other and with the body portion of the strip adhering to the other two walls. 80

3. A folding box of paper-board or like 90 material, comprising a blank scored and cut to form a plurality of walls two of which are adapted to be folded down onto each other to positions in which they are in planes substantially perpendicular to the planes of 95 two adjoining walls, in combination with a stay comprising a strip of textile fabric having a longitudinally bifurcated end the opening in which is substantially semi-elliptical with the longitudinal axis of the opening running in the general direction of the warp of the strip and the rounded end of the opening facing inward and located substantially at the corner of said four walls and running in the general direction of the woof of the strip and with the forks of said bifurcated end adhering to the two walls which are adapted to be folded down onto each other and with the body portion of the strip adhering to the other two walls. 100

4. A fastening or joining stay for paper-board boxes, said stay comprising a strip of sheet material having a longitudinally bifurcated end the opening in which is substantially U-shaped with the closed end of the opening facing inward, 115

5. A fastening or joining stay for paper-board boxes, said stay comprising a strip of textile fabric having a longitudinally bifurcated end the opening in which is substantially U-shaped with the closed end of the opening facing inward and running in the general direction of the woof of the strip. 120

6. A fastening or joining stay for paper-board boxes, said stay comprising a strip of 125 textile fabric having a longitudinally bifur-

cated end the opening in which is substantially semi-elliptical with the longitudinal axis of the opening running in the general direction of the warp of the strip and the rounded end of the opening facing inward and running in the general direction of the woof of the strip.

Signed at Rochester, in the county of Monroe, and State of New York, this 31st day of July, A. D. 1912.
